UNITED STATES PATENT OFFICE

2,550,385

MEMORANDUM SHEET HOLDER

Herman B. Shepard, Wilkes-Barre, Pa.

Application May 31, 1949, Serial No. 96,306

4 Claims. (Cl. 281—44)

1

The present invention pertains to note books or memorandum devices of the loose leaf type.

The principal object of this invention is to provide a loose leaf container or note book having novel means to select and retain any particular sheet of note paper in a position either for taking notes or for quick reference thereto.

Another object of this invention is to provide a loose leaf container having a hinged cover flap that opens from the top toward the bottom and is therefore more natural and easy to handle in taking notes than the usual side or top pivoted covers of present day note books.

A salient feature of the invention is the provision for use of perforated loose leaf sheets or flexible cards in a cooperative loose leaf container so formed that sheets or cards can be rearranged at will but may also be properly bound and kept together by cooperation with a novel indexing or selecting means.

A still further object of the invention is to provide a loose leaf container or memorandum book having novel plunger or oscillating pin means whereby the hinged cover flap may be conveniently maintained in either a closed or open position.

Other novel features of improvement contributing to the efficiency of operation of the device either in taking notes or making reference thereto will be apparent and readily understood from the following detailed description of the preferred embodiment of the invention taken in connection with the accompanying drawing, in which:

Fig. 1 is a front elevation in perspective illustrating the memorandum device in closed position;

Fig. 2 is a view similar to Fig. 1 but showing the device held in open position by the plunger means;

Fig. 3 is a vertical sectional view taken on the line III—III of Fig. 1 and looking in the direction of the arrows;

Fig. 4 is a similar sectional view taken on the line IV—IV of Fig. 2 looking in the direction of the arrows and clearly illustrating the manner in which the plunger means cooperates with the sheets or cards and the container in the open position;

Fig. 5 is a cross sectional view taken on the line V—V of Fig. 1 looking in the direction of the arrows and showing details in the construction of the container or binder portion;

Fig. 6 is a view of one of the loose leaves or cards used in the memorandum device; and

2

Fig. 7 is an elevation in perspective similar to Fig. 2 but showing a modification of the container construction.

Referring to the drawing, the numeral 8 generally indicates the loose leaf container or binder, which may be made of any suitable material such as plastic, fiber board, cardboard, leather and the like.

The rectangular container 8 is formed with a lower pocket portion 10, side panels 12, back panel 14 and front panel 16, and a bottom 17 joining said panels. In the preferred embodiment, the sides or panels 12 are provided with extensions 13 (Figs. 3 and 4) which are folded and overlapped across the back panel 14 and are secured thereto and to each other by means such as staples 15. This is illustrated best in Fig. 5 of the drawings. The back and front panels 14, 16 are considerably wider than side panels 12.

The front panel 16 has a fold or integral hinge 18 intermediate its length which forms a hinged cover flap 20. The cover flap 20 is provided with a small horizontal slot or opening 22 located centrally of the fold 18. The portion of the front panel 16 below hinge 18 is provided with an integral, horizontal strap 24, preferably formed by slits cut through the front panel 16. Through this strap 24 a plunger or bar 26 is slidably mounted. The plunger 26 includes a head portion 28 and an elongated body portion 30.

There are of course various other ways of mounting a plunger, bar or pin member that can be used to accomplish the required insertion and retraction with respect to the cover slot 22.

Loose paper sheets on thin cards, one of which is shown in Fig. 6, are adapted to fit in the container 8 and these sheets are provided with perforated slots 22a which are similar in size and arrangement to the slot 22 in the front panel 16.

When a number of these paper sheets or cards 32 are placed in the pocket portion 10 with their slots 22a in alignment with the slot 22 of the front panel 16, the memorandum device is ready for use.

In describing the operation of the device, it will be assumed that the plunger or bar 26 is in the full line position shown in Fig. 1. In this position, the body portion 30 extends across the fold 18 and over the outside of cover flap 20, and thus acts to hold said cover flap firmly against the contained sheets 32. To open the device, the plunger 26 is retracted so that the body 30 is completely below the fold 18, as shown in the dotted line position of Fig. 1. The cover flap 20 may then be swung down to the position illus-

trated in Fig. 2 after which the plunger 26 is pushed through the slot or opening 22 into a position that will hold the cover flap 20 partially open and separated from the thus clamped sheets 32. If it is desired to select for use any sheet other than the first, it is necessary only to fold back the cover flap 20 and sheets 32a and to insert the plunger 26 through slot 22 in the panel 16 and the slots 22a of the turned down sheets 32a.

In this manner the separated sheets 32a are held away from the selected sheet 32, as clearly shown in Figs. 2 and 4.

Referring now to Fig. 7, a modification of the memorandum device is shown in which sides 12a of the container 8 are extended and terminate substantially even with the top edge of the back panel 14. In this form the sheets 32 are more completely protected and less likely to be displaced from container 8 of the device.

It will be readily apparent from the above description that the memorandum device or book may be put to a large number of desired uses. For example, it may contain notes to be used when making a public address, the plunger 26 acting to hold the book open to any desired sheet. When used for taking notes it has a decided advantage over known prior books or devices in that each sheet may be used to cover one particular subject, so that at a later time when additional information becomes available, the sheets may be easily removed, rearranged and placed back in the book in any desired order without having to tear or release the sheets from cumbersome securing devices. It is a simple matter to retract the plunger 26, turn down the cover flap 20 and the pages not to be used, and push the plunger through the slots 22 and 22a to maintain the sheets 32a separate.

It is obvious that the memorandum device of this invention may be made in any desired size, depending on the particular use. For example, it may be made small enough to fit in the pocket when used as a memorandum pad or address book, or larger for lecture and classroom use.

Since other equivalent modifications and variations in detail will be prompted by the disclosure which has been made, the present invention is to be limited only to the scope and spirit of the appended claims.

Having thus described my invention, what I claim as novel and desire to secure by Letters Patent of the United States is:

1. A loose leaf container comprising a rectangular pocket portion including front, rear, and side panels and a bottom connecting all of said panels, said front panel having a transverse fold intermediate its length providing a hinged cover flap, and an opening through said cover flap; and a plunger mounted on said front panel below the transverse fold for movement through and out of said opening to maintain said cover flap in an open or closed position.

2. A loose leaf container comprising a rec-

tangular pocket portion including front, rear and side panels and a bottom connecting all of said panels, said front and rear panels each being considerably wider than and extending upwardly well above said side panels, said front panel having a transverse fold intermediate its length and in substantial alignment with the upper edges of the side panels, and an elongated opening through said front panel intermediate the length of said fold; and means including a plunger slidably secured on the outside of the front panel to cooperate alternatively with said opening and the outside of the hinged portion of the front panel to hold said hinged portion in an open or closed position.

3. A notebook comprising in combination a pocket portion, said pocket including front, rear and side panels and a bottom connecting all of said panels, said front and rear panels each being wider than and extending upwardly well beyond said side panels, said front panel being transversely hinged and provided with an opening therethrough intermediate said transverse hinge; paper sheets or cards of a size and configuration to fit into said pocket portion and extend upwardly between the front and rear panels, said paper sheets or cards having perforated openings aligned with the front panel opening; and bar means mounted on the outside of said front panel for movement into and out of the front panel opening and the aligned openings of the paper sheets or cards to separate any number of said sheets or cards.

4. A loose leaf container comprising a rectangular pocket portion including front, rear and side panels and a bottom connecting all of said panels, said front and rear panels each being considerably wider than and extending upwardly well above said side panels, said side panels each having a lateral extension folded over and secured to said rear panel, and said front panel being provided with a central elongated horizontal opening therethrough approximately on a level with the upper edges of said side panels and folded along said opening to form a hinged cover flap, and said front panel being provided with a strap on the outside below said cover flap; and a plunger slidably secured to said front panel by said strap for alternate movement through said opening and out of said opening and over the outside of said cover flap.
